Louis C. STEENBERG
by J. Weatherford
Atty.

UNITED STATES PATENT OFFICE

2,099,775

VEHICLE LIFT

Louis C. Stukenborg, Memphis, Tenn.

Application June 26, 1935, Serial No. 28,427

6 Claims. (Cl. 60—52)

This invention relates to improvements in hydraulic vehicle lifts and particularly to that class of such lifts in which the lifting fluid is pumped from an extraneous reservoir to a jack having a vertically disposed cylinder with a plunger therein, and in which the liquid is forced back into the reservoir by the descent of the plunger and the superstructure carried thereby.

This invention has been illustrated in connection with a lift table or superstructure for raising automobiles for servicing and as is usual in such construction, is shown with the cylinder and other parts of the lift proper below the surface of the ground.

15 The objects of the invention are:

To provide a jack and a reservoir and pump unit adjacent thereto, and integrally connected therewith, whereby the jack, reservoir and pumping unit are a self-contained device which may be installed as a single entity.

20 To provide means in such a unit whereby the pump is at all times submerged and the discharge passageway from the pump to the jack cylinder is of minimum length.

25 To provide over-flow means whereby leakage is substantially prevented from the top of the cylinder.

To provide over-flow means whereby the maximum raise of the jack plunger is hydraulically limited.

30 To provide, in connection with pumping means, release means for allowing return flow from the jack cylinder to the reservoir and screening means in connection therewith, whereby the reverse flow alternately set up by pumping and release automatically clears the screens protecting inflow to the pump.

35 To provide in a jack means for preventing rotation of the plunger relative to the cylinder.

40 The means by which these and other objects are accomplished and the manner of their accomplishment, will readily be understood from the following specification on reference to the accompanying drawings in which,—

45 Fig. 1 is a vertical sectional elevation through the cylinder and plunger of a hydraulic jack and through an associated reservoir and pumping unit.

Fig. 2 is a vertical sectional elevation on a somewhat reduced scale showing the exterior of the jack cylinder and of the reservoir with the two more closely adjacent than shown in Fig. 1.

Fig. 3 is a fragmentary sectional plan on an enlarged scale taken on the line III of Fig. 1.

55 Fig. 4 is a fragmentary sectional elevation on

the same scale as Fig. 3, showing the plunger of the lift in fully raised position.

Referring now to the drawings in which the various parts are indicated by numerals, 10 is a vertical cylinder adapted to be buried in the ground. 11 is a head secured as by welding in the bottom end of the cylinder. 12 is a plunger slidably mounted within the cylinder and guided in its movements by guide rings 13, 14, secured to the cylinder wall. Surrounding the plunger at 10 the upper end of the cylinder is a stuffing box 15 having upper and lower sets of packing, 16 and 17 respectively, which sets are separated by a ring 18 of generally I shaped cross section. The lower packing 17 rests in the bottom of the stuffing box 15, which bottom is shown in part formed by the guide ring 13. The bottom flange of the ring 18 rests on the lower packing 17, the upper packing 16 rests on the upper flange of the ring 18 and the two packings and ring are held in place and compressed by a gland 19 tightened in usual manner as by bolts 20. Mounted on the upper end of the plunger is a superstructure for the support of the load to be raised. This structure may comprise a plate 21, channel members 22 secured thereto as by welding, an additional pair of I beams 23 (only one of which is shown), which are transversely disposed to the channels 22 and secured thereto as by bolts 24, and wheel supporting rails 25 suitably secured to the I beams 23. The web of the ring 18 being of less thickness than the width of the flanges, leaves within the stuffing box 15, inner and outer annular spaces 26 and 27, communication between which spaces is established by openings 28 through the web.

The plunger is preferably hollow and has a lower head 29 which is disposed at a distance above the bottom end of the plunger somewhat greater than the distance between the bottom of the lower guide ring 14 and the tops of the annular space 26. Openings 30 are provided through the wall of the plunger immediately below the head 29 so that when the plunger is fully raised in use, the openings 30 will come into register with the inner annular space 26 and through the openings 28, be in communication with the outer annular space 27. 31 is an over-flow pipe which leads through the outer wall of the stuffing box 15 from the outer annular space 27.

The plunger 12 preferably is held against rotation. To do this a suitable opening is made in the head 29 and a pipe 32 is secured and sealed to the plunger head 29 around this opening and

extended upward adjacent the top of the plunger, the upper end 33 of this pipe being sealed. Secured to the bottom 11 of the cylinder and extending upward therewith and slidably within 5 the pipe 32, is a guide rod 34, this rod and the pipe 32 both being offset from the center of the plunger and cooperating to prevent rotation of the plunger.

Adjacent the cylinder 12 is a tank 40 preferably cylindrical in shape and substantially co-extensive in height with the cylinder 10, including its stuffing box. This tank is preferably placed immediately adjacent the cylinder 14 but in order that its upper end may be made accessible under all conditions it has been shown in Fig. 1 as slightly spaced therefrom so that it may not be covered by superstructure parts. In Fig. 2 a modification is shown in which the tank 40A is more nearly adjacent the cylinder 10A, 15 this having been accomplished by disposing over the plunger 12A a channel shaped plate 21A of reduced width as compared with the plate structure first shown, and cutting away portions of the flange of the gland 19A.

20 The lower end of the tank 40 is closed by a head 41 and spaced above this head is an annular flange 42. Resting on this flange and secured and sealed thereto as by bolts 43 and nuts 44 is the flange 45 of a pump 46. The pump flange 45 and the annular flange 42 cooperate to divide the tank 40 into an upper chamber or reservoir 47 and a comparatively restricted lower chamber 48, the lower chamber 48 being in free communication through a pipe 49 with the lower end of the 35 pump cylinder 10.

40 The bolts 43 which are used to secure the flange 45 to the annular flange 42 preferably extend upward toward the top of the reservoir 40 and form guides by means of which the pump 46 may be lowered into proper position prior to securing its flange 45 in place. Preferably such extending bolt portions are not threaded, the lower ends only being enlarged and threaded in usual manner. Also the upper ends of the rods may be 45 threaded to receive support nuts 50. 51 is an annular steady plate adapted to be supported on these nuts and 52 are nuts securing the plate in place. 60 is a pump shaft which is connected at its upper end by a coupling 61 to the shaft 62 of an electric motor 63.

50 The motor 63 is suitably supported as by a plate 64 to which it may be secured as by bolts 65, the plate 64 being adapted to be supported on an annular flange 66, preferably welded to the 55 casing 40, and to be secured thereto as by bolts 67. Preferably an annular shell 68 is secured to the underside of the plate 64 as by welding and depends therefrom around the motor 63, the annular shell 68 together with the plate 64 to which 60 it is secured, forming a bell entirely surrounding the motor and depending therebelow. From the motor suitable circuit wires 70 lead through the plate 64, being hermetically sealed where they pass therethrough, and through a suitable conduit 71 to a control switch 72 located at a convenient point suitably remote from the lift structure. The intake to the pump 46 leads from the chamber 47 through a suitable screen 73 and the discharge from the pump through a screen 74 65 below the flange 45 and within the chamber 48. Disposed within the casing of the pump 46 is a release valve 75A, which may be opened by depressing the rod 75. The rod 75 leads to the top 70 of the reservoir and there terminates beneath an arm 76 which is mounted on a shaft 77 disposed

within a protecting pipe 78. The shaft 77 preferably extends to some distance remote from the lift structure and is provided with an additional arm 79 by which it may be turned to actuate the arm 76 and depress the rod 75.

5 The over-flow pipe 31 leading from the stuffing box 15 is connected into the reservoir portion 47 of the tank 40. 80 is a filling pipe which is provided with a removable cap 81. This pipe may lead into any portion of the reservoir chamber 47, but is shown as leading in through the overflow pipe 31. In Fig. 2 the pipe corresponding to the pipe 31 is given the numeral 31A and the other corresponding parts are also designated by the addition of the same letter A.

10 It will be understood that the detail of the pump and motor, and of the control switch form no part of the present invention and are therefore not shown.

15 It will further be understood that the remaining detail except as it may be specifically set out in any claim is also typical only and introduced for the purpose of illustration.

20 In constructing the device the cylinder 10 and the tank 40 are assembled into a unitary structure. Preferably after completion of the cylinder the overflow pipe 31 and the pipe 49 are secured thereto as by welding, and these pipes are also secured to the tank 40 in similar manner. Should the pipe 49A as in the modified form 30 shown in Fig. 2 be too short to permit access between the cylinder and tank for welding, such welding may be done from the interior of the tank before the tank bottom 41 is welded in place.

25 To install, a hole of suitable size is excavated and preferably a concrete foundation 82 placed in the bottom as a support. The cylinder unit and tank unit is lowered into place, the jack cylinder being brought truly vertical and ordinarily the earth back-filled and tamped to hold the unit 40 in such position. When in place concrete 83 is ordinarily poured around the upper end of the unit, this concrete being usually a part of the floor which surrounds the unit. After the cylinder and tank unit has been placed, the plunger 12 is placed in the jack cylinder, the packing and other parts placed in the stuffing box and tightened, and the superstructure installed. If the pump is not in place in the reservoir the holes in the flange 45 of the pump are engaged with the 50 ends of the guide rods 43, and the pump is lowered by means of the pump shaft 60, to place on the annular flange 42, a suitable packing gasket (not shown) having been interposed. When in place the nuts 44 are dropped over the rods 43 and thereafter tightened by a suitable socket wrench. With the pump in place the upper ends of the rods 43 may be engaged by the annular steady plate 51, and this plate be secured by the nuts 52 to steady the upper end of such guide rods. The motor 63 is then lowered to place and the two parts of the coupling 61 engaged. The plate 64 is bolted down to the flange 66 and a cover plate 83 placed and secured.

55 The reservoir 47 is then partially filled with oil and with the filling cap 81 still removed, the pump is operated to fill the chamber 48, the lower end of the piston and the cylinder 10 around the plunger. The operation of the pump is continued, additional oil being added if found necessary until the plunger is raised to full height, this height being limited by register of the holes 30 with the annular space 26, and entrained air in the cylinder and plunger are allowed to escape to the atmosphere, until all air has been fully ex- 70 75 75

elled. Pumping is then stopped and the plunger lowered by shifting the lever 19 and depressing the rod 15 to open the release valve. Preferably such excess of oil is placed in the reservoir as to fully cover the pump at all times.

5 What I claim is:

1. In a lift, a jack and a rigidly connected reservoir and pumping unit; said jack comprising a vertically disposed cylinder, a plunger slidably mounted therein and projecting thereabove and a superstructure carried by said plunger; said unit comprising a vertically disposed tank closely adjacent said cylinder and rigidly secured thereto, said tank being of substantially equal height with 10 said cylinder and being divided transversely into a lower chamber of restricted height and a relatively much larger reservoir thereabove, passageways respectively connecting said chamber with the lower end of said cylinder and the upper end 15 of said cylinder with said reservoir, means within said tank operable to transfer liquid from said reservoir through said chamber to said cylinder and means for establishing return flow from said cylinder and chamber to said reservoir, a stuffing 20 box at the upper end of said cylinder, two sets of packing in said stuffing box, means spacing said packings apart, said means being perforated to permit flow from the interior to the exterior thereof, and said passageway connecting said 25 cylinder and reservoir being in communication with the openings through said spacing means, plunger guiding means within said cylinder spaced below said stuffing box, said plunger being hollow from its lower end upward a distance at least 30 equal to the distance from the bottom of said guiding means to a point midway between said packing means, and said piston having openings adjacent the upper end of said hollow portion through its circumferential wall.

40 2. In a lift, a jack and a rigidly connected reservoir and pumping unit, said jack comprising a vertically disposed cylinder, a plunger slidably mounted therein and projecting thereabove, and a superstructure carried by said plunger; said unit comprising a vertically disposed tank closely adjacent said cylinder and rigidly secured thereto, a passageway connecting the upper end of said cylinder with said tank, means within said tank operable to transfer liquid from said tank to said cylinder, and means for establishing return flow 45 from said cylinder to said tank; a stuffing box at the upper end of said cylinder, two sets of packing in said stuffing box, means spacing said packings apart, said means having openings to 50 permit flow from the interior to the exterior thereof, and said passageway connecting said cylinder and reservoir being in communication with the openings through said spacing means, plunger guiding means within said cylinder 55 spaced below said stuffing box, said plunger being hollow from its lower end upward a distance at least equal to the distance from the bottom of said guiding means to a point between said packing means, and said piston having openings adjacent the upper end of said hollow portion through its circumferential wall.

3. In a fluid actuated jack, comprising a cylinder-plunger assembly, a reservoir for fluid, a pump for transferring fluid from said reservoir to 60 said assembly and manually controlled release means for said fluid, said pump having a screened intake from said reservoir, and a screened outlet

to said assembly, said release means bypassing said pump, and being disposed between said screened intake and said screened outlet and housed by the screens thereof.

4. In a fluid actuated jack, comprising a cylinder-plunger assembly, a reservoir for fluid, a pump for transferring fluid from said reservoir to said assembly and release means for said fluid, said pump having a screened intake from said reservoir, and a screened outlet to said assembly, 10 said release means bypassing said pump, and being disposed between said screened intake and said screened outlet and housed by the screens thereof.

5. In a lift, a jack and a connected reservoir 15 and pumping unit; said jack comprising a vertically disposed cylinder, a plunger slidably mounted therein and projecting thereabove and a superstructure carried by said plunger; said unit comprising a vertically disposed tank, said tank being 20 divided transversely into a lower chamber of restricted size and a relatively much larger reservoir thereabove, passageways respectively connecting said chamber with the lower end of said cylinder and the upper end of said cylinder with 25 said reservoir, means within said tank operable to transfer liquid from said reservoir through said chamber to said cylinder and means for establishing return flow from said cylinder and chamber to said reservoir, a stuffing box at the upper end of said cylinder, two sets of packing in said stuffing box, means spacing said packings apart, said means being perforated to permit flow from the interior to the exterior thereof, and said passageway connecting said cylinder and reservoir being 30 in communication with the openings through said spacing means, plunger guiding means within said cylinder spaced below said stuffing box, said plunger being hollow from its lower end upward a distance substantially equal to the distance from the bottom of said guiding means to 35 a point above the lower of said packing means, and said piston having openings adjacent the upper end of said hollow portion through its circumferential wall.

6. In a lift, a jack and a connected reservoir and pumping unit, said jack comprising a vertically disposed cylinder, a plunger slidably mounted therein and projecting thereabove, and a superstructure carried by said plunger; said unit comprising a vertically disposed tank, a passageway connecting the upper end of said cylinder with said tank, means within said tank operable to transfer liquid from said tank to said cylinder, and means for establishing return flow from said cylinder to said tank; a stuffing box at the upper end of said cylinder, two sets of packing in said stuffing box, means spacing said packings apart, said means having openings to permit flow from the interior to the exterior thereof, and said passageway connecting said cylinder and reservoir being in communication with the openings through said spacing means, plunger guiding means within said cylinder spaced below said stuffing box, said plunger being hollow from its lower end upward a distance at least equal to the distance from the bottom of said guiding means to a point between said packing means, and said piston having openings adjacent the upper end of said hollow portion through its circumferential wall.

LOUIS C. STUKENBORG.
